CLAIM

The ornamental design for a breast pump, as shown and described.

DESCRIPTION

FIG. 1 is a perspective view of a breast pump showing our new design;

FIG. 2 is another perspective view thereof;

FIG. 3 is another perspective view thereof;

FIG. 4 is another perspective view thereof;

FIG. 5 is a front elevational view thereof;

FIG. 6 is a rear elevational view thereof;

(Continued)

FIG. 7 is a left side elevational view thereof;
 FIG. 8 is a right side elevational view thereof;
 FIG. 9 is a top plan view thereof; and,
 FIG. 10 is a bottom plan view thereof.
 The broken lines in the drawings depict portions of the
 breast pump and form no part of the claimed design.
